UNITED STATES PATENT OFFICE.

ERNEST POLESKE AND SEARS POLESKE, OF MANILLA, IOWA.

GRINDING MACHINE.

Application filed January 14, 1928. Serial No. 246,724.

This invention relates to machines for grinding grain, feed and the like, and has more particular reference to grinding machines wherein the grinding is performed by pivoted hammers which are so mounted that they can swing back when they encounter an obstruction or a hard object.

The primary object of the present invention is to provide improved means for pivotally mounting the hammers so that they will be kept in spaced relation.

Another object is to provide an improved form of pivoted hammer which is light and simple in construction, and which may be formed from a flat bar and secured in position without the aid of separate fastening and spacing devices.

A further object is to provide a construction and arrangement of hammers whereby a most efficient grinding operation may be had with the expenditure of a minimum amount of power.

The invention consists in the novel form, combination and arrangement of parts hereinafter more fully described, shown in the accompanying drawings and claimed.

In the drawings:

Figure 1 is a top plan view of a grinding machine embodying the present invention.

Figure 2 is an elevational view looking toward the left of Figure 1.

Figure 3 is a section on line 3—3 of Figure 1.

Figure 4 is an enlarged fragmentary section, showing the form of the hammers and the manner of mounting them on alternate ones of the pivot rods.

Figure 5 is a view somewhat similar to Figure 4, showing the manner of mounting the hammers on the remaining pivot rods; and

Figure 6 is an enlarged perspective view of one of the hammers.

Referring more in detail to the drawings, 5 indicates the casing or housing having an interior grinding surface 6, 7 the hopper for feeding material thereinto, 8 the bottom grate or screen having openings through which the reduced or ground material passes, and 9 the 45 spout which leads the ground material from the machine. A shaft 10 carries end disks 11 and an intermediate polygonal plate 12 between which are pivotally mounted the hammers 13 on rods 14 which fit in and pass 55 through holes in the corners of the plate 12 and have reduced ends 15 which fit into open-

ings in the end disks 11. In this way the pivot rods cannot move through the end disks, and the intermediate plate 12 will brace the pivot rods and act to agitate the 60 material when the machine is operated.

Each hammer 13 consists of a flat bar bent into J-shaped and having alined openings 16 in the spaced opposed portions thereof so that the hammer may be slipped onto 65 the pivot bar and be free to swing thereon. The hammers are disposed on each pivot rod so that the longer leg of each hammer flatly engages the longer leg of the next adjacent hammer and the shorter leg of each hammer 70 flatly engages the shorter leg of the next adjacent hammer as shown in Figures 4 and 5. The hammers are thus mounted and maintained in the desired relation without the aid of separate fastening and spacing means, 75 and, due to the spaced relation of the legs of the hammers, they will yield laterally to a desirable limited degree. The longer legs of the hammers on alternate pivot rods are staggered relative to the longer legs of the 80 hammers on the remaining pivot rods, so as to provide for a most efficient grinding operation with minimum resistance and consumption of power. This relation is effected by placing the first or end hammers 85 on said alternate pivot rods with their shorter legs in contact with the adjacent end disk 11 as shown in Figure 4, and placing the similar hammers on said remaining pivot rods with their longer legs in contact with 90 the said adjacent disk 11 as shown in Figure 5.

Minor changes may be made within the scope of the appended claims.

What we claim as new is:

1. A grinding machine comprising a 95 housing having a grinding chamber, disks rotatably mounted in said chamber, pivot rods extending between said disks, a plurality of hammers pivotally mounted in contiguous relation on said pivot rods between said disks, said hammers comprising flat J-shaped bars presenting opposed spaced portions having alined openings therein through which the pivot rods extend.

2. A grinding machine comprising a housing having a grinding chamber, disks rotatably mounted in said chamber, pivot rods extending between said disks, a plurality of hammers pivotally mounted on said pivot rods between said disks, said hammers comprising flat J-shaped bars having alined 100 105 110

openings in opposed spaced portions thereof through which the pivot rods extend, the longer leg of each hammer being flatly engaged with the longer leg of the next adjacent hammer.

3. A grinding machine comprising a housing having a grinding chamber, disks rotatably mounted in said chamber, pivot rods extending between said disks, a plurality of hammers pivotally mounted on said pivot rods between said disks, said hammers comprising flat J-shaped bars having alined openings in opposed spaced portions thereof through which the pivot rods extend, the longer leg of each hammer being flatly en-

gaged with the longer leg of the next adjacent hammer and the longer legs of the hammers on alternate ones of said pivot rods being staggered relative to the longer legs of the hammers on the remaining pivot rods.

4. A hammer for grinding machines comprising a single strip of metal bent into J-shape and presenting spaced opposed portions having alined transverse pivot openings.

In testimony whereof we affix our signatures.

ERNEST POLESKE.
SEARS POLESKE.
